UNITED STATES PATENT OFFICE.

CHARLES WESLEY JONES, OF GLEN RIDGE, NEW JERSEY.

DESIGN FOR A SETTEE FRAME OR SIMILAR ARTICLE.

Application filed February 14, 1929. Serial No. 30,062. Term of patent 7 years.

To all whom it may concern:

Be it known that I, CHARLES WESLEY JONES, a citizen of the United States, residing at Glen Ridge, in the county of Essex and State of New Jersey, have invented a new, original, and ornamental Design for a Settee Frame or Similar Article, of which the following is a specification, reference being had to the accompanying drawing, forming part thereof.

The drawing shows in perspective view a settee frame embodying my new design.

I claim:

The ornamental design for a settee frame or similar article, as shown.

In witness whereof, I have hereunto set my hand.

CHARLES WESLEY JONES.
